SMOKING ARTICLE

Walter Maurey Henley, Winston-Salem, N.C., assignor to
 R. J. Reynolds Tobacco Company, Winston-Salem,
 N.C., a corporation of New Jersey
 No Drawing. Filed Nov. 14, 1960, Ser. No. 68,664
 6 Claims. (Cl. 131—17)

This invention relates to a smoking article and has for an object the provision of a smoking article or composition having an improved aroma and flavor.

It is well known in the tobacco art that the domestic tobaccos which are exemplified by burley, Maryland, flue-cured, bright leaf or Virginia tobaccos are low in flavor as compared with the so-called oriental or aromatic tobaccos which are imparted from Turkey, Greece, Bulgaria, Yugoslavia, Rhodesia and Russia. Accordingly, it has been common practice in the tobacco industry to prepare blends of domestic and oriental tobaccos in order to provide cigarettes which have desired flavoring and aroma characteristics. Accordingly, it is a further object of this invention to provide a domestic tobacco which has an enhanced flavor and aroma.

A further object of this invention is the provision of a smoking article, such as a cigarette or cigar, a component part of which has been treated in order to enhance the flavor and aroma of the article when smoked.

An additional object of this invention is to provide a tobacco which has been treated in such a manner as to impart a desired cedarlike odor or smoothing or cooling effect which is pleasing to the smoker.

A further object of the invention is the provision of a domestic type tobacco having added thereto a chemical compound which imparts a pleasing cedarlike odor and cooling effect to the tobacco smoke.

Further and additional objects will appear from the following description and the appended claims.

In accordance with one embodiment of this invention, a domestic tobacco or smoking article is provided to which has been added or which has been treated with a small amount of 2,3,4a,5,6,6a,7,8,9,10,10a,10b-dodecahydro - 3,4a,7,7,10a - pentamethyl - 1H - naphtho[2,1-b]pyran. The chemical structure of the above referred to compound may be represented by the following formula:

For convenience the compound is hereinafter referred to in this specification as compound I. It is chemically related to sclareol which latter is a compound contained in the flowering parts of *Salvia sclarea*. Compound I may be prepared from sclareol by the method essentially as disclosed in Ruzicka et al., *Helv. Chim. Acta*, 25, 621 (1942). In accordance with this method, 53.7 grams of 4 - (decahydro - 2 - hydroxy - 2,5,5,8a - tetramethyl - 1 - naphthyl)-2-butanone [referred to in the Ruzicka et al. article as oxyketone (II)] and 0.3 gram of platinum dioxide catalyst were added to 150 milliliters of glacial acetic acid. The mixture was allowed to stand 10-15 minutes in order to convert the ketone to 4a,5,6,6a,7,8,9,10,10a,10b - decahydro - 3,4a,7,7,10a - pentamethyl - 1H - naphtho[2,1-b]pyran. The hydrogenation was conducted at room temperature at an initial hydrogen pressure of 70 lbs./sq. in. The reaction stopped after a hydrogen uptake of approximately 0.2 mole. The reaction mixture, after removal of the catalyst by filtration, was poured

2

into 500 milliliters of water. After neutralization of the acetic acid with K_2CO_3 , the product was extracted with ether and the ether was evaporated to yield 50.8 grams of 2,3,4a,5,6,6a,7,8,9,10,10a,10b - dodecahydro - 3,4a,7,7,10a-pentamethyl-1H-naphtho[2,1-b] pyran (compound I).

Because of the presence of an asymmetric carbon atom at position 3 in the pyran nucleus of compound I, there are two diastereoisomers possible. One has a melting point of 81-82° C. while the other melts at 44-45° C. 10 The higher melting point isomer is the predominant isomer formed in the process indicated above where platinum dioxide is the hydrogenation catalyst. If a catalyst consisting essentially of palladium on charcoal is used, the lower melting point isomer is largely produced. These 15 isomers and other diastereoisomers of compound I and their mixtures are included as tobacco additives within the scope of this invention.

In accordance with this invention, compound I is added to tobacco or applied to a smoking article or its component parts in amounts to provide a product which contains about 0.001 to about 1.0 percent by weight of the additive.

Preferably the amount of additive is between 0.02 and about 0.3 percent by weight in order to form a tobacco product having a desired flavoring and aroma.

20 The additive may be applied to tobacco in any suitable manner and preferably in the form of a liquid solution or suspension by spraying, dipping or otherwise. The additive may be incorporated at any step in the treatment of the tobacco but is preferably added after aging, curing and shredding and before the tobacco is formed into cigarettes.

Likewise it will be apparent that only a portion of the tobacco need be treated, and the thus treated tobacco may be blended with other tobaccos before the cigarettes are formed. In such case the tobacco treated 30 may have the additive in excess of the amounts above indicated so that when blended with other tobaccos the final product will have the percentage within the indicated range.

In accordance with one specific example of this invention, an aged, cured and shredded burley tobacco is sprayed with a one percent ethyl alcohol solution of the above described compound I in an amount to provide a tobacco composition containing 0.07 percent by weight of the additive on a dry basis. Thereafter the alcohol is

40 removed by evaporation and the tobacco is manufactured into cigarettes by the usual techniques. It has been found that the cigarette when prepared as indicated has a desired and pleasing cedarlike odor which is detectable and pleasing in the main and side smoke streams when the cigarette is smoke. The smoke is also smooth and cool.

It will be particularly apparent that the manner in which the additive is applied to the tobacco is not particularly important since, as indicated, it may be done in the form of spraying or dipping, utilizing suitable suspensions or solutions of the additive. Thus water or volatile organic solvents, such as alcohol, ether, acetone, volatile hydrocarbons and the like, may be used as the carrying medium for the additive while it is being applied to the tobacco. Also, other flavor and aroma-producing additives, such as those disclosed in United States Patents Nos. 2,766,145, 2,905,575, 2,905,576 and 2,978,365 may be incorporated into the tobacco with the additive of this invention.

65 While this invention is particularly useful in the manufacture of cigarette tobacco, it is also suitable for use in connection with the manufacture of pipe tobacco, cigars and other tobacco products. Also the invention has been particularly described with reference to the addition of compound I directly to tobacco. However, it will be apparent that the compound may be applied to the paper of a cigarette or the wrapper of a cigar. Also it may be

incorporated into the seam paste for a cigarette. Thus a smoking article is provided which includes both compound I and tobacco although in every instance compound I need not be admixed with the tobacco as above specifically described.

It has been discovered that for certain applications, compound I has advantages over the specific cyclic ether disclosed in Giles United States Patent No. 2,905,575 as a tobacco additive. Thus compound I herein disclosed produces a very low odor at room temperature and the flavoring properties for the most part become apparent only during smoking. The odor is one that may be characterized as cedarlike. Also compound I imparts a smoothing and cooling effect to the tobacco smoke and this effect is similar to that produced by menthol but less pronounced. The flavorant is particularly useful for incorporating into smoking articles prepared from domestic tobaccos as distinguished from the more highly aromatic oriental or Turkish tobaccos.

While particular embodiments of this invention are disclosed above, it will be understood, of course, that the invention is not to be limited thereto, since many modifications may be made, and it is contemplated, therefore, by the appended claims, to cover any such modifications as fall within the true spirit and scope of this invention.

I claim:

1. A smoking article comprising tobacco and a small amount of 2,3,4a,5,6,6a,7,8,9,10,10a,10b-dodecahydro-3,4a,7,7,10a-pentamethyl-1H-naphtho[2,1-b]pyran sufficient to impart a cedarlike odor to a smoker.
2. A tobacco having added thereto a small amount of 2,3,4a,5,6,6a,7,8,9,10,10a,10b-dodecahydro-3,4a,7,7,10a-

pentamethyl-1H-naphtho[2,1-b]pyran sufficient to impart a cedarlike odor to a smoker.

3. A domestic smoking tobacco having added thereto between about 0.001 and 1.0 percent by weight of 2,3,4a,5,6,6a,7,8,9,10,10a,10b-dodecahydro-3,4a,7,7,10a-pentamethyl-1H-naphtho[2,1-b]pyran sufficient to impart a cedarlike odor to a smoker.

4. A process for improving domestic smoking tobacco which comprises admixing therewith a small amount of 2,3,4a,5,6,6a,7,8,9,10,10a,10b-dodecahydro-3,4a,7,7,10a-pentamethyl-1H-naphtho[2,1-b]pyran sufficient to impart a cedarlike odor to a smoker.

5. A process for improving the flavor and aroma of smoke from tobacco which comprises adding thereto in the form of a liquid suspension between about 0.001 and 1.0 percent by weight of 2,3,4a,5,6,6a,7,8,9,10,10a,10b-dodecahydro-3,4a,7,7,10a-pentamethyl-1H-naphtho[2,1-b]pyran sufficient to impart a cedarlike odor to a smoker.

6. A process for improving the flavor and aroma of smoke from tobacco which comprises adding thereto in the form of a liquid solution between about 0.001 and 1.0 percent by weight of 2,3,4a,5,6,6a,7,8,9,10,10a,10b-dodecahydro-3,4a,7,7,10a-pentamethyl-1H-naphtho[2,1-b]pyran sufficient to impart a cedarlike odor to a smoker.
